(57) **CLAIM**

The ornamental design for an dish warm tray, as shown and described.

DESCRIPTION

FIG. 1 is a front, left, bottom perspective view of the dish warm tray, showing my new design;

FIG. 2 is a rear, right, top perspective view thereof;

FIG. 3 is a front elevational view of the reduced scale thereof;

FIG. 4 is a rear elevational view of the reduced scale thereof;

FIG. 5 is a left side view of the reduced scale thereof;

FIG. 6 is a right side view of the reduced scale thereof;

FIG. 7 is a top plan view of the reduced scale thereof;

FIG. 8 is a bottom plan view of the reduced scale thereof;

FIG. 9 is an enlarged view of detail 9 in FIG. 1;

FIG. 10 is an enlarged view of detail 10 in FIG. 2;

FIG. 11 is an enlarged view of detail 11 in FIG. 4;

FIG. 12 is an enlarged view of detail 12 in FIG. 6; and,

FIG. 13 is an enlarged view of detail 13 in FIG. 8.

The dashed broken lines in the figures are for the purposes of illustrating portions of the dish warm tray and form no part of the claimed design.

The short-short-long dashed broken lines immediately adjacent to the claimed areas in the views represent the boundaries of the design and form no part of the claimed design. The dash-dot-dash broken lines are for notating enlarged views and form no part of the claimed design.

1 Claim, 13 Drawing Sheets
